G. A. BERGMAN

SCRAPER FOR RANGES

Filed June 3, 1925

WITNESS
Robt. S. Woolsey

INVENTOR
GUSTAVE A. BERGMAN
by James R. Townsend
his attorney.

UNITED STATES PATENT OFFICE.

GUSTAVE A. BERGMAN, OF LOS ANGELES, CALIFORNIA.

SCRAPER FOR RANGES.

Application filed June 3, 1925. Serial No. 34,654.

This invention relates to that type of scraper, with which, eatable substances, such as batter, dough, grease, etc. may be removed from a range, cooking plate, etc.

5 An object of my invention is to provide a novel scraper, in which the particles as they are removed will be prevented from falling onto the cleaned part of the stove and again adhering thereto and also prevented from flying back upon the hands of 10 the person using the scraper.

Another object is to provide a novel and useful scraper with interchangeable blades, which may be varied to suit different occasions of which may be replaced when worn.

Further objects are to provide a scraper, which is simple in construction, inexpensive to manufacture, and efficient in operation.

Other objects, advantages and features 20 of invention may appear from the accompanying drawing, the subjoined detail description and the appended claims.

The accompanying drawing illustrates the invention.

25 Figure 1 is a bottom plan view of my scraper.

Fig. 2 is a side elevation of the same.

Fig. 3 is a side view of a modified form 30 of scraping blade.

Fig. 4 is a side view of still another form of scraping blade.

Fig. 5 is a sectional view taken on line x5, Fig. 2.

Fig. 6 is a fragmentary top plan view of 35 my scraper.

My scraper 1 comprises a handle of any desirable material either metal or wood and has integrally formed therewith a wide jaw portion 3 which has a transverse saw slot 4 formed therein adapted to receive a metallic blade 5, of approximately the same width as the jaw. This blade may have a square edge 6 as shown in Fig. 2, or an angular cut edge 6' as in Fig. 3, or a 40 pointed edge 6'' as in Fig. 4.

A shield 7 is mounted on the top of the jaw 3, and is preferably formed of metal, such as spring steel or sheet iron. This shield is curved upwardly as at 8 and thence downwardly to the edge 9, which is curled or rolled upwardly to form a bead and such rolled edge 9 extends beyond the lower or outer edge 6 of the blade 5.

50 The blade 5 and shield 7 are spaced apart at their secured ends by the thickness of

material of the jaw 3 between the slot 4 and the upper face of said jaw, and the edges 6, 9 are spaced apart approximately the same distance as the secured ends.

Two or more bolts 10 extend through the 60 jaw 3, blade 5 and the clamp bar α , and wing nuts 11 screwed onto the bolts 10 draw the bar α against the end of the shield 7, which is inserted between the jaw 3 and the bar α , as shown in Fig. 2, and thereby securely 65 holds said shield and blade in position. By removing the wing nuts 11 the bolts 10 may be removed and the blade 5 replaced or repaired or interchanged as the case may be.

In use the blade 5 is passed over the surface of the range, plate, etc., to remove particles of batter, dough and the like. The particles as they leave the point of the blade 5 are prevented from flying away from the area already cleaned and onto other articles 70 that may be on the surface cleaned, and are also prevented from flying back onto the hands or arms of the person using the scraper.

That is, the particles as they are removed 80 by the blade 6 will hit against the shield and will be deflected downwardly again into the path of the blade, to be collected thereon.

The extending and curved end 9 will also 85 prevent the shield from gouging into the range or plate top, if during the operation of the scraper the shield should come into engagement with said top.

I claim:

1. A scraper comprising a handle; a jaw integrally formed with said handle; said jaw having a slot formed therein; a blade mounted in said slot; a clamp bar; a shield mounted between said jaw and clamp bar 95 and extending over said blade; bolts extending through said jaw, blade, and clamp bar; and nuts screwed onto said bolts.

2. A scraper comprising a handle; a jaw integrally formed with said handle; said jaw having a slot formed therein; a blade mounted in said slot; a clamp bar; a shield mounted between said jaw and clamp bar and extending over said blade; bolts extending through said jaw, blade, and clamp bar; and nuts screwed onto said bolts; said shield having an upward bend adjacent the center thereof, and being curled upwardly at the outer end thereof.

3. A scraper comprising a handle; a jaw 110

integrally formed with said handle; said jaw having a slot formed therein; a blade mounted in said slot; a clamp bar; a shield mounted between said jaw and clamp bar and extending over said blade; bolts extending through said jaw, blade, and clamp bar; and nuts screwed onto said bolts; the

outer edge of said shield projecting beyond the outer end of said blade.

In testimony whereof, I have hereunto set ¹⁰ my hand at Los Angeles, California, this 27th day of May, 1925.

GUSTAVE A. BERGMAN.
